UNITED STATES PATENT OFFICE.

PAUL L. CROWE, OF DULUTH, MINNESOTA.

FURNACE-WALL.

SPECIFICATION forming part of Letters Patent No. 668,498, dated February 19, 1901.

Application filed August 29, 1900. Serial No. 28,411. (No model.)

To all whom it may concern:

Be it known that I, PAUL L. CROWE, a citizen of the United States, residing at Duluth, in the county of St. Louis and State of Minnesota, have invented certain new and useful Improvements in Furnace-Walls; and I do hereby declare the following to be a full, clear, and exact description of the invention, such as will enable others skilled in the art to which it appertains to make and use the same.

My invention relates to improvements in furnaces, and more particularly to the construction of the walls of such furnaces; and it has for its object the construction of furnace-walls particularly adapted to inclose traveling grates and to embody draft-flues and water-boxes for the utilization of otherwise-wasted heat and the prevention of clinkers at the sides of the grate, and, further, for the protection of the metallic furnace-front and fuel-port.

It consists of a furnace-closure comprising overhanging side walls and overhanging bridge-walls, the overhanging portions of the inner faces of said walls adjoining the grate and the bridge-wall overhanging the end of the grate, the overhanging portion of the side walls, however, not overhanging the grate, but closely adjoining the sides of the grate-frame and extending from the front of the furnace as far back as the bridge-wall.

It also consists in a furnace provided with suitable walls adapted to inclose an adjustable grate, of water-boxes arranged upon the inner surfaces of the said walls, so as to prevent the formation of clinkers, water-boxes also arranged in the front and rear of the grate-frame to protect the furnace-front and the bridge-wall from the effects of excessive heat, the said furnace-walls being also provided with draft-flues for introducing sufficient air to the combustion-chamber to obtain practically a perfect combustion of the fuel.

It also consists in certain other novel constructions, combinations, and arrangements of parts, as will be hereinafter fully described and claimed.

In the accompanying drawings, Figure 1 represents a longitudinal vertical section through a furnace provided with walls constructed in accordance with the present in-

vention. Fig. 2 represents a transverse vertical section through the same, taken upon a line passing through the bridge-wall. Fig. 3 55 represents a horizontal transverse section through the walls of the furnace, a portion of the arches at the front and rear of the furnace being shown in elevation and parts of the said arches being broken away. Fig. 4 60 is a detail sectional view showing a slightly different way of constructing the bridge-wall employed in such a furnace. Fig. 5 represents a partition-wall which is employed when a series of furnaces are arranged to form a 65 battery. Fig. 6 represents a longitudinal vertical section through a furnace, the walls of which are adapted to support a tubular boiler.

In constructing a furnace with which I desire to supply improved means for protecting 70 the walls and supplying air to the combustion-chamber I usually form the same with side and back walls made of brick, while the front of the furnace is preferably closed by a front plate, preferably of metal, but which 75 may be made of brick or part brick and part metal. As seen in the drawings, such a furnace may be formed of side walls 1 1 and a rear wall 2, the outer portions of which are built of ordinary brick, while the inner surfaces of the same are preferably provided 80 with fire-brick adapted to withstand the effects of high degrees of heat. In the front the side walls 1 1 are connected by a front plate 3, which is formed with a suitable aperture 85 to accommodate the forward end of a grate-frame 4, which projects through the said opening. In adapting the walls of the furnace to a grate which is adjustable and not connected with the walls thereof, a space 90 is arranged between the grate-frame and the said walls, as at 5. The upper parts of these spaces on each side of the grate are reduced and almost closed by forming overhanging portions 6 6 in the side walls. In the overhanging portions of each of the side walls I incorporate a water box or tube 7, having one face flush with the inner face of the wall and exposed to the combustion-chamber of the furnace. Said water-boxes preferably continue 95 backward in the furnace-wall and penetrate the rear wall 2 of the said furnace-wall. At their forward ends they project through the front plate or wall of the furnace. The ends 100

of these water-boxes are provided with suitable hand-holes, which are closed in any suitable manner, as at 8 8, so that easy access may be had to the water-tubes for cleaning 5 or otherwise operating upon the same. These side-wall boxes 7 7 may be horizontal or laid at an incline, and the overhanging portions 6 6 of the side walls may be made correspondingly horizontal or may be laid at an incline 10 in accordance with the arrangement of the water-boxes. The side-wall water-boxes extend from a plane slightly below the lower level of the upper face of the grate to a plane slightly above the highest level of the upper 15 face of the grate and are primarily designed to prevent the formation of clinkers along the side walls adjacent to the grates. The bridge-wall 9 of the furnace, which is arranged transversely between the side walls 20 11 at the rear of the grate-frame, is also preferably protected at its edge by means of a water-box, as 10. The bridge-wall water-box lies upon and across the side-wall boxes 7 7 and has one face exposed to the combustion-chamber. It may form the lower 25 edge of the overhanging portion of the bridge-wall or its upper face may be exposed and be arranged flush with the top of the bridge-wall behind it, as seen in Fig. 1 of the drawings. 30 If desired, however, the upper face of the water-box 10 may be covered with brick, or a brick arch, as 11, may be arranged over the water-box forming a part of said bridge-wall, without departing in the least from the spirit 35 of the present invention. The latter construction is illustrated in Fig. 4 of the drawings, in which the bridge-wall is shown a little higher than the one illustrated in Fig. 1 of the drawings. The formation of the bridge- 40 wall depends largely upon the construction of the boiler to be used in the furnace, it being necessary to arrange certain minor modifications to accommodate the general setting of various styles of boilers. The ends of the 45 bridge-wall box preferably penetrate the side walls 1 1 of the furnace and are likewise provided at their ends with hand-holes and suitable closures, as 12 12, for stopping the same. At the front of the furnace the combustion-chamber is also preferably lined by 50 a water-box, as 13, the said water-box lying upon and across the side-wall boxes 7 7 and against the front wall of the furnace. It is especially designed to protect the metallic 55 front and the edges of the fuel port or opening above the front end of the grate. The ends of the front box 13 also penetrate the side walls 1 1 of the furnace, and it is provided at its ends with hand-holes and closures, as 14 14. Each of the water-boxes surrounding the combustion-chamber is connected with the water-box adjoining it by suitable means—as, for instance, by means of expanded tubes—as seen at 15 in the drawings, so 60 that the contents of the water-boxes may be passed freely from one box to the other. The said boxes may be connected with the boiler

by any convenient construction, so that a circulation from the boiler may be passed through the same or the boxes may be provided with an inlet or outlet for water or steam independent of the boiler. When the walls are used to support a boiler having cylindrical flues, the boiler being also cylindrical, I prefer to continue the front fire-arch 16 forward over the said front water-box 13; but when mounting other styles of boilers the arrangement of the arch may be varied, as will be hereinafter more fully described. 70 75

In the construction of the walls of the furnace the overhanging portions 6 6 of the side walls are vertically pierced, as at 17 17, in a number of places along their length, the passages thus formed passing upwardly to points opposite the combustion-chamber 85 above the grate and being provided with laterally-opening passages, as 18 18, which direct air passing through the passages 17 into the combustion-chamber. The entrance of these passages is preferably above the side water-boxes and may be at varying distances from the same, according to the height of the combustion-chamber at different points. The flues thus formed provide draft-passages from the space beneath the grate leading to the 90 combustion-chamber, the air becoming heated in its passage through the furnace-walls. Other draft-flues may also be arranged in the side walls having vertical portions, as 17^a, and laterally-extending delivery end portions 17^b, 100 which open into the combustion-chamber. The lower ends of the vertical portions 17^a connect with longitudinally-arranged horizontal inlet-passages 17^c, which extend to the front furnace. These passages are open at 105 their front ends to receive air from outside the said furnace-walls. The air thus introduced will pass through these passages in the wall, becoming heated thereby and entering the combustion-chamber at a higher temperature for assisting in the combustion of the fuel. 110

The front wall of the furnace is preferably metallic and may, if desired, be arranged with a brick lining behind it, or it may be constructed entirely of brick, the said front wall 115 3 being preferably provided with a large central aperture or passage, as 19, for the passage of the front end of a grate and to form the fuel inlet or port above the said grate. 120 The front arch 16 is arranged immediately above the grate at any suitable distance, extending to the rear for a short space and reaches from one side wall to the other. It is preferably formed of fire-brick, so as to 125 withstand the effects of heat.

I sometimes arrange furnaces in series to form a battery, in which instance there is a longitudinal central wall, as seen in Fig. 5 of the drawings, which is formed upon each side 130 with overhanging portions 20 20, the said overhanging portions having water-boxes 21 21, arranged with their inner faces exposed to the combustion-chambers upon each side

of the said central wall. In such instances the inner ends, respectively, of the front and bridge wall boxes resting in the said central wall are preferably closed and may abut 5 against each other. The portion of the furnace-walls in the rear of the bridge-wall may be of any desired construction, but is substantially the same as the well-known construction of the walls of a common gas-com-10 bustion chamber in any stationary flue or tube boiler, except that the side water-boxes are continued along the inner face of the said side walls, being incorporated therein and piercing the rear wall of the furnace, or may, 15 if desired, terminate under the overhanging portion of the bridge-wall. Said central wall is also preferably carried up to the lower plane of the overlying boiler-tubes in the tubular boilers or so as to divide the boilers 20 into flue-boilers, which central wall may also, if desired, be provided with air-passages substantially similar to those in the side walls.

In accommodating the wall and other protecting water-boxes to a water-tube boiler, 25 for instance, such as is illustrated in Fig. 6 of the drawings, the arrangement of the parts is varied very little. In such an instance the side water-boxes 22 extend from front to rear in the same manner as above described upon 30 either side of the grate-frame 4; but instead of employing overhanging brick portions for supporting the said boxes they may rest upon metallic standards, as 23 23, if preferred, though overhanging portions may be em-35 ployed in their place. The front and rear wa- 30 ter-boxes 24 and 25, respectively, rest upon the side water-boxes, as before, and are ex- 35 posed to the combustion-chamber upon their inner faces. The front water-box 24 may, if 40 desired, form in some instances a lower front header for the tube-boiler 26 and be connected with its circulation, though it will be apparent that it need not be connected with the 45 said boiler if not desired, but an independ- 40 ent lower horizontal boiler-header may be su- 45 perimposed upon said front water-box. In 50 arching boilers of this character above the combustion-chamber I preferably construct 55 the front arch 27 in a slightly different man- 50 ner from that above described. As seen in 55 Fig. 6 of the drawings, the said front arch is 60 preferably doubled upon itself, the under portion 28 thereof extending forwardly again to a point in close proximity to the front water- 65 box 24. The lower portion 28 of the said arch, however, does not touch the said box, but leaves a passage-way between the two parts. The side air-flues of such a furnace prefer- 70 ably communicate with the space 29 thus 75 formed between the upper and lower portions of this arch. The air entering this passage 80 29 is free to discharge itself through the pas- 85 sage 30 in the rear of the water-box 24 into the combustion-chamber near the front end 90 of the grate.

As seen in Fig. 3 of the drawings, the arches may rest upon suitable metallic backs, as 31

31, which are preferably hollow to admit of the passage of air through the same, the said backs upon opposite sides of the furnace be- 70 ing connected by tie-rods 32 32 for anchoring the ends of the said arches.

A furnace constructed with walls as above described is especially adapted for the use of grates which are mounted in frames adapt- 75 ed to be adjusted to different heights in the furnace. This is especially the case when traveling chain-grates are employed, the front ends of which project beyond the front wall of the furnace in order to receive their charges 80 of fuel. The arrangement of the water-boxes around the combustion-chamber so as to line the walls of the furnace are well adapted for protecting the said walls against excessive 85 heat and for preventing the formation of 90 clinkers.

Having thus described the invention, what is claimed as new, and desired to be secured by Letters Patent, is—

1. A furnace formed with side and end walls, 90 the said side walls being formed with in- 95 wardly-projecting overhanging portions ad- 100 joining the grate, water-boxes arranged in the said walls and resting on the overhanging portions and having their inner surfaces ex- 105 posed to the combustion-chamber, and trans- 110 versely arranged water-boxes at the front and rear of the combustion-chamber for protect- 115 ing the bridge-wall and the front wall of the 120 furnace.

2. A furnace comprising side and rear walls and having a suitable front, inwardly-extend- 125 ing overhanging portions formed upon the in- 130 inner faces of the side walls and arranged ad- 135 jacent to the grate, longitudinally-arranged 140 water-boxes above the overhanging portions in the said side walls having their inner faces 145 exposed to the combustion-chamber, trans- 150 versely-arranged front and rear water-boxes 155 resting upon the side-wall water-boxes, the 160 said front and rear boxes protecting the 165 bridge-wall and the furnace-front from the 170 heat of the combustion-chamber, and means 175 for gaining access to the interior of the said 180 water-boxes, substantially as described.

3. A furnace comprising suitable walls, in- 185 wardly-extending overhanging portions formed on the inner surface of the side walls 190 adjacent to the furnace-grate, protecting wa- 195 ter-boxes supported on the overhanging por- 200 tions, the side walls being provided with air- 205 passages extending upwardly behind the wa- 210 ter-boxes and adapted to discharge air into 215 the combustion-chamber, end water-boxes ar- 220 ranged at the front and rear of the combus- 225 tion-chamber so as to protect the furnace-front 230 and the bridge-wall of the furnace from the 235 heat-combustion chamber, substantially as 240 described.

4. A furnace comprising suitable walls, 245 water-boxes arranged upon the inner faces 250 of the side walls, end water-boxes arranged 255 transversely of the furnace and penetrating 260 the side walls thereof, the said end water-

boxes resting upon the side water-boxes, means connecting the said water-boxes, whereby a circulation of fluid may be accommodated through the said boxes, the said boxes 5 extending entirely around the combustion-chamber, substantially as described.

5. A furnace comprising side walls, and end walls, a front arch arranged above the furnace-grate, a bridge-wall arranged at the rear 10 of the same, water-boxes lining the inner faces of the side walls, the front wall and the bridge-wall of the furnace, the said water-boxes penetrating the side and rear walls of the furnace, so that their ends are accessible, 15 the said water-boxes being provided at their ends with hand-holes, suitable covers for closing the said hand-holes, the structure being such that the walls of the furnace will be protected at every point entirely around the 20 combustion-chamber by the water-boxes from clinkers and excessive heat, and access may be had to the interior of the said boxes for cleaning them, substantially as described.

6. A furnace having side and end walls, overhanging portions formed upon the inner 25 faces of the side walls adjacent to the furnace-grate, air passage-ways formed in the said overhanging portions of the side walls for conducting air from the space beneath the furnace-grate to the combustion-chamber, the 30 said walls being also provided with passages extending into the same from the front and supplying air to vertical air-passages also arranged in the said side walls and adapted to discharge air above the grate in the combustion-chamber, the construction being such that sufficient air may be provided to produce a practically perfect combustion in the furnace.

In testimony whereof I hereunto affix my 40 signature in presence of two witnesses.

PAUL L. CROWE.
